UNITED STATES PATENT OFFICE.

CLARENCE V. JOHNSON AND THOMAS C. CAIN, OF YATES CENTER, KANSAS.

AMUSEMENT DEVICE.

Application filed January 22, 1923. Serial No. 614,225.

To all whom it may concern:

Be it known that we, CLARENCE V. JOHNSON and THOMAS C. CAIN, citizens of the United States, residing at Yates Center, in 5 the county of Woodson and State of Kansas, have invented certain new and useful Improvements in Amusement Devices; and we do declare the following to be a full, clear, and exact description of the invention, such 10 as will enable others skilled in the art to which it appertains to make and use the same.

Our invention has for its principal object to provide a unique form of amusement device which may be converted at will for use 15 either as a child's teeter or a merry-go-round.

In carrying out the above end, a rotatable support is provided for upper and 20 lower teeters which are disposed at right angles to each other, a further aim being to construct these teeters of central sections and adjustable end sections, the latter serving to lock the teeters against oscillation 25 when moved inwardly to the maximum, permitting the device to be used effectively as a merry-go-round.

A further object is to mount seats on the 30 ends of the teeters in such a manner that they may be turned to face either longitudinally or transversely of said teeters, according to the manner in which the device is being used.

A further aim is to provide a device of 35 the character set forth which may be readily disassembled and packed in a compact manner for storage and shipment.

With the foregoing in view, the invention resides in the novel subject matter herein- 40 after described and claimed, the description being supplemented by the accompanying drawings.

Figure 1 is a top plan view of a device constructed in accordance with our invention.

Figure 2 is a side elevation, parts being removed and in vertical section.

Figure 3 is an enlarged vertical sectional view on line 3—3 of Fig. 1.

Figure 4 is a horizontal section as indicated by line 4—4 of Fig. 3.

Figure 5 is a detail side elevation partly in section, showing the device for use as a teeter, whereas in the other views, it is set 55 for use as a merry-go-round.

Figure 6 is a detail vertical transverse

section as indicated by line 6—6 of Fig. 3.

Figure 7 is a perspective view of the inner end of one of the outer sections of one of the teeters.

In the drawings above briefly described, the numeral 1 designates a suitable base which is preferably formed of sections detachably secured together by dowel pins 2 and one or more bolts 3, so that the base may 60 be readily disassembled for shipment. By means of a suitable vertical pivot 4, a rotatable post 5 is centered upon the base 1, said post having a base 6 between which and the base 1, we provide suitable bearings, 70 such as casters or the ball-bearings 7. It will be understood that a suitable retainer may be provided for these bearings to prevent accidental loss and disarrangement thereof. Also, the pivot 4 may have a flat 75 spring retainer so that no nuts are necessary.

An upper teeter 8 and a lower teeter 9 at right angles thereto, are fulcrumed between their ends upon the post 5. Each of these teeters consists of a central section formed of two parallel side boards 10 and a pair of adjustable end sections which include boards 11 resting on the upper edges of the boards 10, longitudinally slotted bars 12 secured by bolts or the like 13 to the lower sides of the boards 11 and received between the end portions of the side boards 10 and bolts 14 passing through said side boards and through the slots of said bars for ad- 85 justably clamping the latter and the boards 11 in place, while permitting relative ad- justment of said boards according to the weight of the children playing thereon.

The inner ends of the boards 11 are pref- 90 erably formed with notches 15 to snugly re- ceive the post 5 when said boards are ad- justed inwardly to the maximum, and the boards of the lower teeter, in the construc- 100 tion here shown, are provided with notched blocks 16 suitably secured thereto and adapted when moved inwardly to the maxi- 105 mum, to receive the post 5 and contact with the lower side of the upper teeter 8. Thus, both of the teeters are held against oscilla- tion and the entire device may be successfully and amusingly used as a merry-go-round.

On the ends of the several seat boards, we 110 prefer to mount appropriate seats 17 hav- ing hand grips 18, these seats being connect- ed to the boards by vertical bolts or other

pivots 19, so that they may be swung to face longitudinally of the teeters when the latter are to be used as such, or may be turned to face transversely of said teeters when the entire device is to be employed as a merry-go-round.

Preferably used in connection with the details above described, is a coiled spring 20 which may be brought into play to connect one end of one of the teeters with the base 6, thus forming a counter-balance for this teeter if it is to be used by only one child or if the difference in weight of two children upon this teeter, is great.

15 By constructing the device in or substantially in the manner shown and described, it may be simply and inexpensively manufactured and marketed, may be compactly packed for shipment, for instance by parcel post, may be quickly and easily set up for use, and may be converted at will for use as a merry-go-round or a teeter, producing a great deal of amusement. If desired, provision may be made for operating the 25 merry-go-round by a hand crank, foot levers or pedals.

As excellent results may be obtained from the details disclosed, such details may well be followed. However, within the scope of 30 the invention as claimed, numerous minor changes may be made.

We claim:

1. An amusement device comprising a ro-

tatably mounted support, an upper teeter fulcrumed thereon, and a lower teeter fulcrumed on said support at an angle to said upper teeter, said lower teeter having a pair of slides engageable with the under side of the upper teeter to simultaneously lock the two against oscillation.

2. An amusement device comprising a rotatably mounted support, an upper teeter fulcrumed thereon, and a lower teeter fulcrumed on said support at an angle to said upper teeter, one of said teeters having a 45 pair of end sections adjustable inwardly and outwardly and engageable with the other teeter when moved inwardly to the maximum, whereby to lock the two teeters against oscillation.

3. An amusement device comprising a rotatable post, and a teeter fulcrumed thereon, said teeter having a pair of longitudinally adjustable end sections movable inwardly into engagement with said post to 55 prevent oscillation of the teeter.

4. A teeter comprising a central section having spaced side members, a pair of bars adjustably held between said side members at opposite ends of the latter, and boards 60 secured upon said bars and contacting with the upper edges of said side members.

In testimony whereof we have hereunto affixed our signatures.

CLARENCE V. JOHNSON,
THOMAS C. CAIN.
